ILLUMINABLE PLANTER

Paul J. Howard, Los Angeles, Calif.

Application September 27, 1957, Serial No. 47,900

Term of patent 14 years

(Cl. D35—3)

FIG. 2.

FIG. 3.

FIG. 4.

Figure 1 is a front elevational view of an illuminable planter showing my new design, the rear being substantially the same and the broken line representation of a support being for the purpose of illustration only.

Figure 2 is a side elevational view thereof on an enlarged scale, the other side being substantially the same.

Figure 3 is a top plan view of Fig. 2.

Figure 4 is a bottom plan view of Fig. 2.

The dominant features of my design reside in the full line portions of the drawing.

I claim:

The ornamental design for an illuminable planter, as shown and described.
